(Cl. D3—9)

To all whom it may concern:

Be it known that I, Maurice Fixler, a citizen of the United States and a resident of the city of Chicago, in the county of Cook and State of Illinois, have invented a new, original, and ornamental Design for an Embroidered Medallion or the like, of which the following is a specification, reference being had to the accompanying drawing forming a part thereof.

On the drawing, the figure is a plan view of the embroidered medallion or the like, showing my new design.

I claim:

The ornamental design for an embroidered medallion or the like, as shown.

MAURICE FIXLER.
